UNITED STATES PATENT OFFICE.

GEORGE D. MOULTON, OF MELROSE, MASSACHUSETTS.

DESIGN FOR A STATUETTE.

51,073.

Specification for Design.

Patented July 24, 1917.

Application filed March 15, 1917. Serial No. 155,105. Term of patent 3½ years.

To all whom it may concern:

Be it known that I, GEORGE D. MOULTON, a citizen of the United States of America, residing at Melrose, in the county of Middlesex and State of Massachusetts, have invented a new, original, and ornamental Design for a Statuette, of which the following is a specification, reference being had to the accompanying drawing, forming part thereof.

Figure 1 is a view in front elevation of a

statuette illustrating my new design. Fig. 2, is a side view. Fig. 3, is a top plan view.

I claim:

The ornamental design for a statuette as shown.

In testimony whereof I affix my signature in presence of two witnesses.

GEORGE D. MOULTON.

Witnesses:

L. K. HALEY,
HENRY C. THOMSON.
